(57) **CLAIM**

We claim the ornamental design for a beverage dispenser door, as shown and described herein.

DESCRIPTION

FIG. 1 is a left front perspective view of a beverage dispenser door showing our new design;

FIG. 2 illustrates a right front perspective view of the beverage dispenser door of FIG. 1;

FIG. 3 illustrates a left side elevation view of the beverage dispenser door of FIG. 1;

FIG. 4 illustrates a front elevation view of the beverage dispenser door of FIG. 1;

FIG. 5 illustrates a right side elevation view of the beverage dispenser door of FIG. 1;

FIG. 6 illustrates a rear elevation view of the beverage dispenser door of FIG. 1; and,

FIG. 7 illustrates a top view of the beverage dispenser door of FIG. 1.

The broken line showing of the rest of the beverage dispenser is included for the purpose of illustration and forms no part of the claimed design.
